UNITED STATES PATENT OFFICE.

SAMUEL J. BENS, OF NEW YORK, N. Y.

FUEL TANK.

Application filed February 4, 1925, Serial No. 6,815. Renewed November 16, 1926.

My present invention relates to a fuel tank for use with devices which in the course of their use, are required to be rotated through an angle of 90° or less, and 5 has a particular adaptation to the fuel tank as applied to the mechanism of the engine used with a power driven chain saw.

It is common knowledge that where an engine is to be supplied with fuel from a tank, 10 and both tank and engine are subjected to rotation during operation, the feed of the fuel to the carburetor or other mixing device, is uneven which causes irregular and unsatisfactory operation.

15 My invention has for its principal object to remedy the above defects, and further to provide a tank in which the liquid is maintained at a nearly constant level, and will operate with equal efficiency at any position 20 within an arc of 90°, and also in the provision of a constant level attachment which will operate with equal efficiency at any position in this angular limitation.

25 Further objects and advantages will be brought out as the specification proceeds.

To this end my invention includes a supply tank of substantially rectangular shape in which one of its diagonals is arranged normally in a vertical position so 30 that one corner of the tank maintains a minimum low position throughout the rotation of 90° in the plane of the tank. The invention further consists in the provision of a constant level attachment whereby air is admitted to that portion of the tank above the liquid level, which thus allows the liquid to feed through the tank exit to the carburetor, or other attachment, in a novel and useful manner. The invention further consists in 35 the construction, combination, and arrangement of parts hereinafter described, and particularly pointed out in the claims.

I have illustrated in the accompanying drawings, the preferred form of my invention, although it is to be understood that this is merely exemplary of the principle involved, and I do not wish to be limited strictly thereto.

40 In these drawings:—

45 Figure 1 is a side elevation of a tank embodying my invention.

Fig. 2 is a fragmentary sectional elevation of the valve and associated mechanism of the tank of Fig. 1.

50 Fig. 3 is a view similar to Fig. 2 at an angle of 90° thereto.

Fig. 4 is a fragmentary sectional elevation of the filler cap and air relief valve of the tank of Fig. 1.

Referring now more particularly to the form illustrated, I have shown a main supply tank at 1 of substantially rectangular configuration which may be of any desired thickness or depth consistent with the purposes to which the tank is put and the capacity desired. A filler orifice 2 is provided at the upper portion of the tank which is further provided with a threaded cap 3 which compresses a washer 4 so that an air tight joint may be made.

At the lower corner of the tank 1, when arranged in a position so that one of the diagonals thereof is in substantially vertical position, I provide a casting 5 fixed in any suitable manner thereto. To the casting 5 is affixed regulating mechanism 6 as by means of bolts 7 with a gasket interposed between the parts 5 and 6 in order to insure a tight joint therebetween.

The casting 5 is provided with an aperture 80 9 which forms the exit for the fuel within the tank 1. This aperture 9 is covered by a screen 10 held between the parts 5 and 6 so that the fuel in feeding through the exit, is filtered or strained of any extraneous 85 material.

In the fixture 6 is provided a chamber 11 which I shall term a feed chamber. This chamber is provided with a port 12 which communicates with ports 13 in a rotatable 90 valve 14 provided with a handle 15, which allows communication between port 12 and the opening 16 leading to the carburetor or other suitable device. The port 16 is provided with an enlargement 17 into which 95 may be threaded a nipple 18 or other suitable fixture, as circumstances will dictate.

A chamber 19 is also formed in the fixture 6 and which I shall term the constant level chamber, and is closed by the plate 20 bolted as at 21, or by other suitable means to the fixture 6, and provided with a gasket 22 in order to insure a tight joint therewith. The constant level chamber 19 is also provided with a port 23 which communicates with the port 13 and also the port 12. It will be obvious that when the valve 14 is in the position indicated in Fig. 3, communication between the said chamber 11 and the constant level chamber 19 will be permitted, but 110 when the valve 14 is rotated at an angle of 90° in either direction, communication be-

tween the ports 12 and 23 is prevented by reason of the fact that the solid portion of the valve 14 abuts the lower part of the wall 24 and effectively cuts off communication 6 between these ports.

From the constant level chamber 19 rises an air tube 25 in substantial alignment with the vertical diagonal of the tank 1, the upper portion of the air pipe 25 terminating 10 within an extension 26 at the top corner of the tank so that the end of the pipe and the pipe's periphery is spaced from the inner wall of the extension 26.

In the plate 20 which is secured to the 15 fixture 6, I also provide a short length of pipe 27 which allows communication between the outside air and the constant level chamber 19, all for a purpose to be more fully described hereinafter.

20 The operation of the device is as follows:—

The tank 1 having been filled through the opening at its upper portion, and the cap 3 having been screwed down against the gasket 4 so as to form an air tight joint, it will be apparent that the fuel in the tank 1 will feed down through the aperture 9 filling the chamber 11, passing through the ports 12 and 23, and rising in the chamber 19 until 25 it reaches a level indicated by the line A. The fuel also passes through the port 13 in the valve 14 and the passage 16 and fixture 18 to the carburetor, so that fuel is available for that part of the mechanism as soon 30 as the engine or other means is started.

Inasmuch as the cap 3 forms an air tight connection with the part 2 it will be apparent that no further feeding of fuel through the aperture 9 will be possible until air is 40 allowed to enter the tank above the level of fuel therein. This is taken care of by reason of the fact that as the carburetor uses the fuel passing to it through the fixture 18, the level indicated at A in the constant level 45 chamber 19 will lower which will expose the lower end of the pipe 25 so that outside air may pass down through the pipe 27 and up the pipe 25 relieving the vacuum above the upper level of the liquid in the tank 1, which 50 allows enough fuel to exit through the aperture 9 until the level A has been reached again so as to close the bottom of the pipe 25. It will be apparent therefore, that fuel 55 will only feed from the tank as long as and as fast as it is required by the carburetor.

It will also be apparent that I have provided a tank which may be operated from an inclination where one side next the feed fixture is horizontal to the point when the adjacent side next to the fixture is horizontal

and that the aperture 9 will always be, in any of these positions, the lowermost portion of the tank throughout this rotation and that due to the arrangement of the constant level chamber 19 and the air supplying pipes 27 and 25, the feed and pressure of the fuel remains constant and regular so that the usual objectionable irregular feeding is prevented.

Having thus described my invention, what 70 I claim is:—

1. A fuel tank substantially rectangular in cross section, and having one of its diagonals arranged vertically, a feed fixture affixed to the lower corner of said tank, including a constant level chamber, and means to admit air to the top of the tank above the liquid level controlled from said constant level chamber.

2. A fuel tank substantially rectangular 80 in cross section and arranged with one of its diagonals in a vertical position, a feed fixture affixed to the lower corner of said tank, a feed chamber in said fixture, a constant level chamber in said fixture, hollow 85 means extending from said constant level fixture to the space above the level of the liquid in said tank, a port allowing communication between the feed chamber and the constant level chamber, and means to 90 close said port.

3. A fuel tank substantially rectangular in cross section and having one of its diagonals arranged in a vertical position, a feed fixture secured to the lower corner of said tank, a feed chamber communicating by a port to a constant level chamber, a tube allowing communication between said constant level chamber and the space above the fuel level in the tank, said constant level 100 chamber also being vented to the outside air, and a port from the feed chamber to a point outside said feed fixture.

4. A fuel tank having a feed fixture secured to the lowest point thereof, a feed 105 chamber within said fixture, a constant level chamber within said fixture, a valved port connecting the two chambers, an air feed tube extending from the constant level chamber to the space above the level of the 110 fuel in the tank, the lower end of said tube being normally closed by the level of liquid in the constant level chamber, and a vent extending from above the normal level of liquid in the constant level chamber to the 115 outside air, and a common exit for fuel from said constant level and feed chambers through said port.

In testimony whereof I affix my signature.
SAMUEL J. BENS.
